2 Claims. (Cl. 313—113)

Our invention relates to an electric lamp and, in particular, to a lamp having an iodine containing gas filling and a filament wound entirely or partially into a helix and provided with one or more terminal members sealed in a base or pinch therein.

With suitable proportioning and suitably chosen operating conditions the presence of a small amount of iodine in the free or combined state in such a lamp produces the so-called iodine circulation. This results in that any tungsten of the filament which has vaporized and found its way onto the wall of the bulb is returned to the filament which has two important advantages. First, there is comparatively little blackening of the bulb; and second, the filament is regenerated by the tungsten returned during operation of the lamp. Consequently, in lamps of this kind a filament of comparatively high power can be accommodated in a comparatively small bulb, while the life of the lamp can be made comparatively long.

The temperature distribution in such a lamp plays a decisive part in the production of a satisfactory iodine circulation. Especially, contact of the iodine with metals liable to be adversely affected by it should be avoided, since this may detract from the life of the lamp.

A principal object of our invention is to provide a lamp having a gas-filling containing iodine which is of simplified construction in which the metal parts are relatively resistant to the action of molecular iodine in various temperature ranges.

A further object of our invention is to provide a lamp of the aforesaid type in which the light distribution is such that only light from the central portion of the filament is transmitted through the envelope.

In a lamp according to the invention, each of the ends of the filament extends in a base support or in the envelope pinch in which it is secured to a terminal member sealed therein. Further, in accordance with the invention, the lamp is provided, at least in the proximity of the part of the filament adjacent a pinch, with means which in the operation of the lamp prevent that part of the filament from radiating light to the space surrounding the lamp, at least on part of the periphery of the lamp envelope extending at right angles to the lamp axis.

Thus, unlike the usual construction of an iodine-filament lamp, in the lamp in accordance with the invention the end of the filament extends into the base or pinch and there is secured to the terminal member sealed therein. As a result, it is not necessary to arrange within the lamp space component parts consisting of other metals which at certain temperatures cannot satisfactorily withstand the action of iodine and the additional advantage is obtained that the manufacture of the lamp is simplified. The metal parts required for a lamp having one filament comprise, in addition to this filament, only two terminal members sealed in the base and two external current supply wires so that a total of four joints are sufficient.

However, the fact that the filament extends into the base or pinch in some applications has the disadvantage that in the operation of the lamp the filament radiates light throughout its entire length, that is to say from the boundary face of a pinch to the boundary face of a pinch. If such a lamp is to be used to produce a sharply

2

defined beam, this phenomenon may be troublesome which is obviated by providing the lamp with the above mentioned means which prevent light from being radiated to certain parts of the space surrounding the lamp.

5 In one embodiment of the lamp in accordance with the invention the lamp envelope is rendered impermeable to light at the portion in close proximity to the base.

In another embodiment the lamp is provided with a screen which may be external to the envelope in close proximity to the base for preventing the transmission of light through the portion of the envelope adjoining the pinch. This screen may be external to the lamp. In order to avoid damage to the screen when in use, however, it is of advantage to accommodate the screen, which preferably is made of platinum, within the bulb. Platinum is capable of withstanding the action of atomic and molecular iodine.

In a further embodiment of very simple construction the end of the filament which extends into the pinch is

20 surrounded by a tube-shaped member, which may be a wire of tungsten wound into a helix. Such a tube-shaped member generally results in that the portion of the filament surrounded by it is only slightly visible, so that the light which may be radiated by this portion is effectively 25 screened by the tube-shaped member. When the tube-shaped member is in contact with the portion of a filament it surrounds, the temperature of this portion of the filament falls to a temperature such that it emits substantially no light.

30 In an embodiment of the lamp in accordance with the invention in which the bulb is made of glass, more particularly hard glass, the tube-shaped member may extend into the pinch almost up to the terminal member. It has been found that the likelihood of the pinch cracking is 35 greatly reduced by this construction.

The lamp in accordance with the invention is particularly advantageous when combined with a substantially parabolic reflector. In this case the lamp is arranged so that its filament, which is at least partially wound into

40 a helix and extends in a straight line, extends along or parallel to the axis of the reflector in the reflector space, while a portion of the filament coincides with or is adjacent to the focus of the reflector. According to the invention in this case, the lamp is further disposed so that the portion of the filament situated between the apex and 45 the focus of the reflector is provided with means which prevent this portion from radiating light to the space surrounding the lamp, at least over that portion of the lamp envelope extending at right angles to the lamp axis.

The invention will now be described with reference to 50 the accompanying drawing, in which:

FIG. 1 shows one embodiment in section of the lamp in accordance with the invention;

FIGS. 2 and 3 show a second embodiment of the lamp in accordance with the invention, FIG. 3 being a cross-sectional view of the lamp taken through the plane III—III of FIG. 2;

FIGS. 4 and 5 show a third embodiment of the lamp in accordance with the invention, FIG. 5 being a cross-sectional view of the lamp taken through the plane V—V of FIG. 4;

FIG. 6 shows a combination of a parabolic reflector and the lamp of FIG. 2.

The lamp shown in FIG. 1 has a tubular envelope 1 which at both ends terminates in flat pinches 2 and 3, respectively, in which the ends of the filament 4 are sealed. Filament 4 comprises a central helically wound portion 4a the ends of which terminate in straight portions 4b and 4c. The portions 4b and 4c project through boundary faces 5 and 6 of the envelope 1 so as to be partly disposed 65 in the pinches 2 and 3 respectively. These filament portions are each secured to a terminal member in the form of

ires 7 and 8, respectively, of greater diameter. At their outer ends the wires 7 and 8 are joined to nickel current-supply wires 9 and 10 respectively. Bulb 1 is provided with a sealed-off exhaust tube which is arranged asymmetrically with respect to the remainder of the bulb to prevent light reflection. The bulb contains a filling gas, e.g. krypton and iodine in the free or combined state in an amount such that when the lamp is operated, so-called iodine circulation is produced in the bulb. As has been mentioned hereinbefore, this reduces blackening of the bulb and has a regenerating effect on the filament.

Because filament 4 extends from terminal member 7 to terminal member 8, a very simple lamp construction is obtained. In certain cases it may be considered a disadvantage that in the operation of the lamp not only the helically wound portion 4a of the filament 4 but also its ends 4b and 4c, insofar as they lie within the boundary surfaces 5 and 6 of the bulb 1, emit light. In the lamp shown in FIG. 1 this disadvantage is obviated by providing each of the ends 1a and 1b of the bulb 1 over a length which is substantially equal to the length of the ends 4b and 4c of the filament 4 respectively, insofar as these ends are situated between the surfaces 5 and 6, with a layer which is impermeable to light and for the sake of clarity is shown by shading in the figure. This results in that the light issuing from the lamp is emitted substantially only by the helically wound portion 4a of the filament and only leaves the bulb through the clear part thereof encircling this portion.

In the embodiment shown in FIGS. 2 and 3 another construction for preventing the radiation of undesired light is used. A slightly curved screen 24 of platinum arranged in the bulb space 25 is secured by means of a thin platinum wire 23 to a terminal member 21 which is incorporated in the left-hand pinch 22 and has the shape of a foil of molybdenum. The screen extends longitudinally through a distance which is about equal to the length of the straight portion 26b of a filament 26 extending in the space 25. Otherwise the construction of the lamp shown in FIG. 2 is similar to that of the lamp shown in FIG. 1. The only further differences are that unlike those of FIG. 1 the terminal members 21 and 27 have the form of foils, and that only one of the straight ends of the filament 26 is screened.

As is shown particularly by FIG. 3, the screen 24 extends at right angles to the longitudinal axis of the lamp and through an angle α with respect to the peripheral direction of the lamp. Consequently, if FIG. 2 shows the operating position of the lamp, the straight filament and 26b will only be prevented from radiating light into the space surrounding the lamp in the upward direction through the angle α .

The embodiment shown in FIG. 4 uses a filament 40 which is helically wound and has a portion 40a which is intended for the emission of light and is shaped substantially in the form of a V. In this embodiment also the straight filament ends 40b and 40c extend into a common pinch 41. In this pinch they are secured to terminal members 42 and 43 in the form of pieces of thicker molybdenum wire to which current-supply wires 44 and 45 of nickel are secured. Bulb 46 is provided with a sealed-off exhaust tube 47.

In this embodiment, in order to prevent the straight filament ends 40b and 40c from radiating light, these ends are surrounded by sheath-shaped members 48 and 49 which each comprise a helically wound tungsten wire. These members surround the straight filament ends 40b and 40c with a small amount of clearance. Any light emitted by the straight filament ends 40b and 40c is rendered invisible by these sheath-shaped members so

that only the helical portion 40a of the filament radiates light. The bulb of this lamp is made of hard glass. The fact that the sheath-shaped members extend into the pinch 41 provides the additional advantage that in the operation of the lamp the hard-glass pinch is less likely to crack than if the straight filament ends 40b and 40c were directly sealed in the hard glass.

FIGURE 6 shows diagrammatically a substantially parabolic reflector 61, the optical axis of which is designated X—X. At the rear this reflector has an aperture 62 for the introduction of a source of light. A plate-shaped holder 63, on which a lamp 66 of the type shown in FIG. 2 is mounted by means of rigid current-supply wires 64 and 65, fits within this aperture. When the holder is arranged in the reflector, the longitudinal axis of a filament 67 coincides with the optical axis X—X of the reflector 61. The focus F of the reflector lies in this axis X—X. The filament 67 is preferably arranged so with respect to the focus F that the rearmost turn of the helical portion 67a of this filament coincides with the focus F. If now the straight end 67b of the filament 67, which end is near the apex of the reflector, is screened upwardly by a screen 68 arranged in the lamp 66, it is ensured that the upper half of the reflector 61 produces no light ray which is at an upwardly directed angle to the reflector axis X—X.

In the arrangement shown, the lower half of the reflector can produce upwardly directed light rays. If this is troublesome, it may be obviated, for example, by shifting the focus of the lower half of the reflector towards the aperture thereof with respect to F.

While we have described our invention with reference to specific examples and embodiments thereof, other modifications will be readily apparent to those skilled in this art without departing from the spirit and scope thereof as defined in the appended claims.

What we claim is:

1. A source of illumination comprising a light-transmissible envelope filled with an iodine-containing gas, an helically-wound filament provided with straight end portions and adapted to glow upon the passage of an electrical current therethrough and positioned within said envelope, a base support within said envelope into which at least one straight end portion of said filament extends, a terminal member sealed within said base support to which the end of said filament is connected, and a relatively light-impermeable screen member constituted of platinum and positioned to intercept light only radiated by said straight end portion of said filament extending into said base support.
2. A source of illumination as claimed in claim 1 wherein said screen is a sheath-shaped member of helically-wound tungsten wire surrounding the portion of said filament extending into said base support.
